ATTORNEY.

UNITED STATES PATENT OFFICE

2,423,352

LATCH

Berthold R. Thiele, Milwaukee, Wis., assignor to
E. R. Wagner Manufacturing Company, Milwaukee, Wis., a corporation of Wisconsin

Application March 27, 1944, Serial No. 528,284

11 Claims. (Cl. 292—96)

1

This invention relates to improvements in latches for boxes or cases and the like, and particularly to latches in which the latch bolt is positively held in either its engaged or disengaged positions.

One object of the invention is to provide a latch in which both a pressing and a turning action are necessary to move the bolt from engaged to disengaged position, or vice versa.

Another object of the invention is to provide a latch in which the bolt is held either in engaged or disengaged position unless pressure is exerted on the bolt or its associated parts before a turning force is applied to rotate the bolt from one position to the other position thereof.

Another object of the invention is to provide a latch in which a locking means positively holds the bolt either in engaged or disengaged position until the locking means is released from the bolt by pressure before the bolt is turned from one position to the other position thereof.

Another object of the invention is to provide a latch which is extremely simple and compact in construction, reliable and effective in operation, attractive in appearance, susceptible of economical manufacture, and which may be readily applied to a box or case and the like.

Objects and advantages other than those above set forth will be apparent from the following description when read in connection with the accompanying drawings, in which:

Fig. 1 is a front elevation of the latch of the present invention applied to a fragment of a box or case;

Fig. 2 is a view similar to Fig. 1 but showing the relation of the several parts in dotted lines;

Fig. 3 is a sectional view taken on the plane of the offset line III—III of Fig. 2;

Fig. 4 is an enlarged fragment of Fig. 3;

Fig. 5 is a top view of the base of the housing enclosing the latch bolt;

Fig. 6 is a front elevation of the latch bolt;

Fig. 7 is a side elevation of the latch bolt;

Fig. 8 is a side elevation of a spring acting on the latch bolt; and

Fig. 9 is a side elevation of the spring shown in Fig. 8.

Referring to the drawings by reference numerals, 20 generally designates a casing serving as a keeper for a latch bolt 21 which is enclosed in a housing generally designated 22. Casing 20 includes a base 26, indicated in dotted lines in Fig. 2 which is provided with a peripheral flange 21 and has portions 28 formed therefrom as prongs for fastening the casing to one portion of the box

5 or case to be latched. The casing base 26 is enclosed by a cover 29 with a flange 30 interfitting the flange 21 of the base, the cover being suitably fastened to the base. The bolt housing 22 likewise includes a base 33 (see Fig. 5) with fastening prongs 34 formed therefrom and with flanges providing walls 35 and 36 substantially defining a circular space, the wall 36 having a straight portion 37 extending therefrom. The base is formed with pairs of sockets 38 and 39 which are preferably on diameters of a circle concentric with the center of the circular space. The bolt housing is completed by a cover 40 with a peripheral flange 41 interfitting with a flange 42 about portions of the edge of the base and the cover is suitably fastened to the base. The housing cover 40 is formed with an opening of smaller diameter than the circular base space and having a function which will appear hereinafter.

10 The latch bolt 21 has a substantially circular body 44 rotatably fitting into the circular space defined by the walls 35 and 36 of the housing base 33 and has an extension or nose 45 providing a hook engaging the casing 20. The bolt body 44 has a handle 46 formed thereon of such size as to be rotatable in the opening through the housing cover 40 and has a pair of notches 47 and 48 formed in the periphery of the bolt body. The handle 46 forms a pocket preferably extending 15 on a diameter of the bolt body for receiving an arcuate-shaped leaf spring 50 with the ends 51 and 52 thereof shaped substantially as semi-spheres to seat in the base socket pairs 38 or 39 and to be movable into and out of the sockets. The bolt notches 47 or 48 are engageable with one or more lugs 55 extending toward bolt housing base 33 from the housing cover 40.

20 When the bolt 21 is assembled in the housing 22 and is engaged with the casing 20, as shown in Figs. 2 and 3, the spring ends 51 and 52 are seated in sockets 38 and the bolt body 44 is held against the cover 40 by the spring 50 acting in the pocket formed by the bolt handle 46. The handle 46 then extends through the opening in the cover 40 a sufficient distance to be grasped 25 by the hand. The cover lug 55 engages in bolt notch 48 and holds the bolt 21 positively in latched position. If pressure is applied on the bolt the arcuate spring 50 tends to straighten which allows disengagement of the lug from the notch and forces the spring ends 51 and 52 out of sockets 38. The bolt can then be rotated counterclockwise to release its hook 45 from the casing 20. If counterclockwise turning of the bolt is continued until bolt hook 45 lies against

base wall portion 37, the notch 47 is brought into position to be engaged by the lug 55 upon release of the pressure on the bolt and the ends of spring 50 are brought adjacent the pair of sockets 39. Release of pressure on the bolt then allows the spring 50 to resume its former arcuate or arched shape and snaps the spring ends 51 and 52 into the sockets 39. The bolt is then positively held in unlatched position until the sequence of pressing, holding, and rotating actions is again performed with the rotating action taking place in a clockwise direction.

It will be seen that the present invention provides a latch which has means for positively holding the latch bolt either engaged with or disengaged from the keeper casing unless a given sequence of actions is performed. Accidental movement of the bolt from either engaged or disengaged position is unlikely because of the sequence of pressing, holding, and rotating actions which are required to move the bolt from one position to the other position thereof.

The holding or locking means includes the lug on the housing and the spring acting on the bolt. The operating means is the handle of the bolt itself.

The structure of the latch bolt and its housing is especially simple and rugged and the parts are so designed as to cooperate in forming a unit in which assembly of the parts automatically produces proper positioning for reliable operation and holds the parts in such position. The keeper casing may be provided with a key-operated locking bar engageable with a notch on the bolt nose, merely as an additional feature without change in the other portions of the latch, thus providing a combined latch and lock retaining all of the advantages of the present structure with the additional function of locking.

Although but one embodiment of the present invention has been illustrated and described, it will be apparent to those skilled in the art that various changes and modifications may be made therein without departing from the spirit of the invention or from the scope of the appended claims.

I claim:

1. In a latch, a housing provided with an opening in one wall thereof, a latching bolt provided with a handle positioned in the opening for centering the bolt in its movements into latching and unlatching positions, a spring interposed between the other wall of the housing and the handle and acting to hold the latching bolt against the wall having the opening therein, means carried by the housing to interengage with the latch bolt to positively lock the same in its latched or unlatched position, said locking means being disengaged by pressing on the handle to free the bolt for rotary movement.
2. A latch comprising a keeper casing, a latch bolt engageable with the casing and having a plurality of notches, a latch bolt housing having a lug engageable in the bolt notches, the housing having a substantially circular space receiving the bolt and having sockets therein, and a spring acting on the bolt and engaging in the housing sockets for holding the housing lug engaged in one of the notches.
3. In a latch, a housing comprising a base defining a space and a cover enclosing the space and having an opening therethrough and a lug extending into the space, a latch bolt having a body portion in the housing space and a handle portion extending through the housing cover

opening, the bolt body having notches engageable with the housing cover lug, and a spring seating on the housing base for urging the bolt body into contact with the housing cover when the housing lug is engaged in a pre-selected bolt notch.

4. In a latch, a housing comprising a base defining a substantially circular space and a cover enclosing the space and having an opening therethrough and a lug extending into the space, a latch bolt having a circular body portion in the housing space and a handle portion extending through the housing cover opening, the bolt body having notches engageable with the housing cover lug, and a spring seating on the housing base for urging the bolt body into contact with the housing cover when the housing lug is engaged in a pre-selected bolt notch.

5. In a latch, a housing comprising a base defining a substantially circular space and a cover enclosing the space and having a circular opening therethrough concentric with the body space and a lug extending into the space adjacent the opening, and a latch bolt having a circular body portion movable in the housing space into and out of contact with the housing cover and having a handle portion extending through the housing cover opening, the body bolt having notches in the periphery thereof engageable with the housing cover lug, and a spring within the housing for urging the bolt body into contact with the housing cover and for keeping the housing lug engaged in a pre-selected bolt notch.

6. In a latch, a housing comprising a base having a plurality of sockets therein and a cover having an opening therethrough, a latch bolt having a body portion movable within the housing and a handle portion extending through the cover opening, and a spring having the ends thereof engageable in the housing base sockets and urging the bolt body into contact with the housing cover.

7. In a latch, a housing comprising a base having a plurality of pairs of sockets therein and a cover having an opening therethrough, a latch bolt having a body portion movable within the housing and having a handle portion extending through the cover opening, and an arcuate spring having the ends engageable severally in the pairs of sockets and seating in the bolt handle for urging the bolt body into contact with the housing cover.

8. In a latch, a housing comprising a base having a plurality of sockets therein and a cover having an opening therethrough and a lug extending therefrom, a latching bolt having a body portion movable within the housing and a handle portion extending through the cover opening, the bolt having a plurality of notches in the body portion for pre-selected engagement with the lug, and a spring having the ends thereof engageable in the sockets and holding one of the notches engaged with the lug.

9. In a latch, a housing comprising a base having a plurality of sockets therein and a cover having an opening therethrough and a lug extending therefrom, a latching bolt having a body portion movable within the housing and a handle portion extending through the cover opening, the bolt having a plurality of notches in the body portion for pre-selected engagement with the lug, and an arcuate spring having the ends thereof engageable in the sockets and having the arch thereof seating in the handle, engagement of the 70 spring ends in one of the pair of sockets corre-

sponding with engagement of the lug in one of the notches.

10. In a latch, a housing with an opening in one wall thereof, a latch bolt with a handle extending through the housing opening and co-acting therewith for guiding rotary movements of the bolt into latched and unlatched positions, and a spring acting between another wall of the housing and the handle for holding the bolt against the said one wall of the housing and holding the handle in the opening therethrough in both the latched and unlatched positions of the bolt.

11. In a latch, a housing with a circular opening in one wall thereof, a latch bolt, a handle extending through the housing opening and co-acting therewith for guiding rotary movements of the bolt into both the latched and unlatched positions, the bolt having a peripheral portion underlying said one housing wall and extending beyond the circumference of the opening therein, and a spring acting between another wall of the housing and the handle for holding the underlying portion of the bolt against the said one

5
6
wall of the housing and holding the handle in the opening therethrough in both the latched and unlatched positions of the bolt.
